DESIGN FOR A TEXTILE FABRIC

Harry Weixel, Brooklyn, N. Y., assignor to Atlas
& Bluhm Inc., New York, N. Y., a corporation of New York

Application October 22, 1938, Serial No. 80,624

Term of patent 3½ years

To all whom it may concern:

Be it known that I, Harry Weixel, a citizen of the United States and a resident of the city of New York, Borough of Brooklyn, county of Kings, and State of New York, have invented a new, original, and ornamental Design for Textile Fabric, of which the following is a specification, reference being had to the accompanying drawing, forming part thereof, in which the single figure in the drawing shows a piece of textile fabric embodying my design, with one repeat unit thereof outlined in dotted lines.

I claim:

The ornamental design for textile fabric, substantially as shown.

HARRY WEIXEL.
